UNITED STATES PATENT OFFICE.

OLGA POPOFF MULLER AND ANDREW PETER POPOFF, OF FLUSHING, NEW YORK, AS-SIGNORS TO DECORATIVE ARTS LEAGUE, OF JERSEY CITY, NEW JERSEY, A CORPORATION OF NEW JERSEY.

DESIGN FOR AN ANDIRON.

Application filed November 18, 1922. Serial No. 4,325. Term of patent 14 years.

To all whom it may concern:

Be it known that we, OLGA P. MULLER and ANDREW P. POPOFF, residing at Flushing, in the county of Queens and State of New York, and at Flushing, in the county of Queens and State of New York, respectively, have invented a new, original, and ornamental Design for Andirons, of which the following is a specification, reference being had to the accompanying drawing, forming part thereof.

The figure is a perspective view of the andiron showing our new design.

We claim:

The ornamental design for an andiron, as shown.

In testimony whereof we have hereunto signed our names.

OLGA POPOFF MULLER.
ANDREW PETER POPOFF,
